UNITED STATES PATENT OFFICE.

SIDNEY A. KELLER, OF NEW YORK, N. Y.

DESIGN FOR A HANDLE FOR BUTTON-HOOKS OR SIMILAR ARTICLES.

SPECIFICATION forming part of Design No. 36,043, dated September 9, 1902.

Application filed August 12, 1902. Serial No. 119,459. Term of patent 7 years.

To all whom it may concern:

Be it known that I, SIDNEY A. KELLER, a citizen of the United States, and a resident of New York, borough of Manhattan, in the 5 county of New York and State of New York, have invented and produced a certain new, original, and ornamental Design for a Handle for Button-Hooks or Similar Articles, of which the following is a specification.

10 In the accompanying drawing I have shown the design applied to the handle of a button-hook.

The characteristic features of my design are the outline of the handle, consisting of 15 compound curves, the head of a winged cherub occupying the upper part of the handle, and floral decoration, consisting of flowers, leaves, and stems, occupying the lower part of the handle, the ornamentation being 20 in relief.

Referring to the drawing, A represents the head of a winged cherub, occupying the upper portion of the handle.

B B represent floral decoration, consisting of flowers, leaves, and stems, and C a plain 25 shield, the ornamentation being in relief.

What I claim is—

The ornamental design for a handle for button-hooks, or similar articles, substantially as shown and described. 30

Signed at New York, borough of Manhattan, in the county of New York and State of New York, this 11th day of August, A. D. 1902.

SIDNEY A. KELLER.
